Attorney.

UNITED STATES PATENT OFFICE.

FRANK J. GILROY, OF BUFFALO, NEW YORK.

TIE-TAMPER.

No. 900,721.

Specification of Letters Patent. Patented Oct. 13, 1908.

Application filed November 26, 1907. Serial No. 403,898.

To all whom it may concern:

Be it known that I, FRANK J. GILROY, citizen of the United States, residing at Buffalo, in the county of Erie and State of New York, have invented certain new and useful Improvements in Tie-Tampers, of which the following is a specification, reference being had therein to the accompanying drawing.

This invention relates to tie tampers adapted to be slid along the rails and clamped thereto at any desired point, the tamping devices being operated by fluid under pressure and supported from the rails upon a transverse member upon which they may slide.

The general object of the invention is to provide at a very low cost simple and effective devices capable of tamping the ballast along the whole length of a tie, including the part beneath the rail.

In the accompanying drawings, Figure 1 shows in elevation a short section of a rail-way with two tampers in position for tamping upon opposite sides of the same tie. Fig. 2 is a cross section between the two tampers of Fig. 1, the apparatus for supporting the tampers being in elevation. Fig. 3 is a plan view of one end portion of the devices seen in Fig. 2. Fig. 4 is an enlarged longitudinal section of a portion of the fluid pressure cylinder, showing a non-cylindrical piston rod. Figs. 5 and 6 are sectional detail views of a portion of the adjustable cylinder and its support. Fig. 7 is a partial view corresponding to Fig. 2 but showing a modified construction.

In these views, A, A represents the rails, B the ties, and C a fluid pressure cylinder provided with valve mechanism and a piston, without novelty, the valve preferably being of the oscillating type and acting automatically with a frequency depending upon the volume and pressure of the fluid admitted.

D is a piston rod carrying a readily detachable tamping tool E which usually has a broad flat working end, and to prevent this end from turning out of a plane parallel to the tie the piston rod is made square or otherwise non-cylindrical.

Air or other fluid is admitted to the cylinder by a hose F and its admission is controlled in the usual way by a valve not

shown. The cylinder is slidably mounted upon a rod G parallel to the ties and supported from and above each rail by a bracket consisting of a broad plate H resting at one end upon the rail head and a second plate H' detachably hinged to the inner end of the plate H and extending downward around the rail head and alongside the inner face of the rail web. The pintle, H², of the hinge is so made as to be readily withdrawn, to permit substituting a different plate for the plate H'. The plate H extends outward horizontally from the rail and in its upper end, which rises to some distance above the plane of the rails, the threaded end of the rod G is detachably fixed by nuts H³, H⁴. This plate is further provided with a stiffening rib H⁵ which also serves as a shoulder to rest against the outer side of the rail head. The plate H' is preferably cut away at H⁶ so that it may pass over a nut when the apparatus is so placed that this is desirable, and is also provided with slots or recesses H⁷ to receive and accurately locate the ends of a fork to be described.

To lock the two hinged brackets to the rails, there is provided a toggle-bar I which has forked ends I' to enter the slots or recesses H⁷ which thus hold the two ends of the toggle-bar at precisely the same distance from the tops of the two rails, and that it may be readily seen whether either rail is lower than the other the toggle-bar is provided with an ordinary spirit lever tube J. One arm of the toggle-bar has a screw K for adjusting the length of the bar, and in order that the apparatus may be locked only when the bar is held down by an attendant, the bar carries a spring L which is easily detached and which reacts against the tie and constantly urges the middle of the depressed bar upward. It is thus impossible, so long as the spring is in place, for the apparatus to be left locked to the rails and thus likely to derail a passing train.

In order that the cylinder may be set at different distances above and at one side of the tie, according to the character of the ballast, the plates H are provided with several holes H⁸ in either of which the rod G may be placed, thus adjusting the angle as well as the height of the tool.

The cylinder has upon the side next the rod G a heavy rib in which is formed a dove-

tail way C' (Fig. 5) in which fits a guide bar M along which the cylinder may be longitudinally adjusted and to which it may be fixed by a setscrew M'. The guide bar is connected to a sleeve N, sliding on the bar G, by a swivel joint of common construction, shown in Figs. 5 and 6, whereby the cylinder may be inclined in its plane of movement along the rod G and thus the ballast beneath the rails be readily tamped from the inside or outside of the rail. When the piston is raised to the upper end of its path, the tamping tool is above the plane of the ties, and by then rocking the cylinder upon the rod G it will be thrown above the plane of the rails and may be carried from one side of the rail to the other. When the tool is thus raised and the middle of the toggle-bar is also raised, the whole apparatus may be pushed along the rails to tamping position alongside a different tie.

In use, two tampers are ordinarily arranged as indicated in Fig. 1, one attendant for each holding down the corresponding toggle-bar and controlling the tamping while a third man moves both cylinders along the rods G. One man readily puts a tamper in place and removes it from the track, and the three easily lift on and off the track the light motor car, not shown.

Fig. 7 shows a form in which vertical brackets O, O' support the rod G which in this case has free ends extending out from the rails approximately to the ends of the ties. In this form the devices tamp between and beneath the rails as before, but they must be transferred to the outer ends of the rod G for tamping outside the rails. In this figure, the plate O', corresponding to the plate H' of the primary form, is shown as plane, and especially adapted for use over a heavy fish plate P and its nuts or bolt heads Q. Such a plate may be quickly substituted for the plate H' of the other form, when desired, if the pintle be withdrawn as before suggested.

In order that the vibration of the rod G may be lessened when tamping near the middle of the tie, I in some instances support it at points over the rails, respectively, by extensible and readily removable struts S, Fig. 2, of any convenient construction.

Many changes may be made without passing the proper limits of my invention and I do not, therefore, wish to limit my claims to the specific embodiment shown.

What I claim is:

1. In tamping apparatus, the combination with a fluid pressure cylinder, a piston working in the cylinder and provided with a non-cylindrical piston rod, a tamping tool carried by the piston rod, and means for supporting the cylinder above the plane of the tie to be operated upon.

2. In a tie tamping apparatus, the combination with a transverse bar, of supports for said bar adapted to rest directly upon the rails, means for clamping the supports to the rails, and a fluid pressure tamping device slidably mounted upon said bar.

3. In tie tamping apparatus, the combination with a transverse bar of a length materially greater than the width of the track, brackets adapted to be clamped to the rails and to support, respectively, the outer ends of the bar, and fluid pressure tamping devices slidably mounted upon said bar.

4. In a tamping apparatus, the combination with a transverse bar, of means for securing the bar to the rails, a fluid pressure cylinder mounted to slide freely along said bar and to swing freely in planes parallel thereto, a piston working in said cylinder, and a tamping tool carried by said piston; whereby ballast may be tamped obliquely beneath the rail.

5. In a tamping apparatus, the combination with a transverse bar, of means for rigidly supporting the same above the rails, means for rigidly clamping the supports to the rails, a cylinder-supporting block mounted to slide along the bar and to swing transversely thereon, and a tool-carrying fluid pressure cylinder mounted upon the block to swing in planes parallel to the bar.

6. In a tamping apparatus, the combination with a transverse bar above the rails when in operative position, means for rigidly supporting the bar from the rails, a cylinder-supporting block mounted to slide along the bar and to rotate about the same, a fluid-pressure cylinder mounted upon the block to swing in planes parallel to the bar, and means for adjusting the cylinder, in a direction parallel to its axis, upon the block.

7. In tie tamping apparatus, the combination with a transverse bar, of means for rigidly supporting the same from the rails, of a tool-carrying fluid-pressure cylinder mounted to slide freely upon the bar and to swing freely in planes transverse thereto and parallel thereto.

8. In a tie tamping apparatus, the combination with a transverse bar, of means for rigidly supporting said bar from the rails, a tool-carrying, fluid pressure cylinder mounted transverse to the bar to slide thereon and to slide in the direction of its own axis and also to swing in planes transverse to the bar and parallel thereto, respectively, and means for at will locking the bar in any position to which it may be adjusted by sliding in the direction of its axis.

9. In a tie tamping apparatus adapted to be readily lifted about by an operator, the combination with a tamping device, of supports for said device, and means for rigidly clamping said supports to fixed portions of the roadway, said means being effective only while held in action by the operator;

whereby the apparatus when left by the operator is always free to be thrown aside by a train.

10. In tie tamping apparatus, the combination with a suitable support, of tamping devices mounted upon said support, two clamps for rigidly securing the support to the rails, respectively, and a toggle-bar free to be flexed by lateral pressure, and adapted to be interposed between the clamps and to force both into engagement.

11. In tie tamping apparatus, the combination with a suitable support, of tamping devices mounted upon said support, two clamps for securing the support to the rails, a toggle-bar adapted to be interposed between the clamps and to force both to engage the rails, means for holding the ends

of the toggle-bar at the same distance from the tops of the rails, and a leveling device attached to the toggle-bar.

12. In a tie tamping apparatus, the combination with a suitable support, of tamping devices mounted upon said support, two clamps for securing the support to the rails, respectively, a toggle-bar adapted to be interposed between the two clamps and to force them into engagement, and a spring arranged to resist straightening of the toggle bar.

In testimony whereof I affix my signature in presence of two witnesses.

FRANK J. GILROY.
